UNITED STATES PATENT OFFICE.

WILLIAM B. STURGIS, OF JOPLIN, MISSOURI, ASSIGNOR TO GENERAL EXPLOSIVES COMPANY, OF CHICAGO, ILLINOIS, A CORPORATION OF DELAWARE.

EXPLOSIVE AND METHOD OF PRODUCING THE SAME.

No Drawing.

Application filed July 23, 1919. Serial No. 312,671.

To all whom it may concern:

Be it known that I, WILLIAM B. STURGIS, a citizen of the United States, and a resident of Joplin, in the county of Jasper and State of Missouri, have invented certain new and useful Improvements in Explosives and Methods of Producing the Same, of which the following is a description.

The object of my present invention is to produce a powerful explosive which shall have a low freezing point and shall be inexpensive to manufacture.

It is known that dinitrochlorhydrin, produced by the nitration of monochlorhydrin, is an explosive having certain desirable properties, including a low freezing point, but because of the expense of producing this explosive as compared with nitroglycerin, for example, its commercial manufacture has been found impracticable.

I have discovered, however, that monochlorhydrin is an extremely efficient solvent for certain inexpensive carbohydrates, such as sugars, and that the nitration of a solution of monochlorhydrin and one or more carbohydrates, such as sugars, produces a very desirable explosive. Its freezing point is exceedingly low, it is easily purified and stabilized, its explosive strength is substantially equal to that of nitroglycerin, and the cost of manufacture is low. This explosive contains dinitrochlorhydrin, and one or more nitrated carbohydrates.

It may be found desirable in some instances to include in the explosive other nitrated components, such, for example, as nitroglycerin. Such an explosive may be produced by nitrating a solution of monochlorhydrin, one or more carbohydrates, and glycerin. The final product obtained from the nitration of this last named solution and subsequent purification, contains nitroglycerin, dinitrochlorhydrin and one or more nitrated carbohydrates. A solution of monochlorhydrin, carbohydrates, and glycerin may be obtained by adding the desired carbohydrates to the solution resulting from the reaction occurring between glycerin and hydrochloric acid when subjected to certain conditions of temperature and pressure. Under ordinary conditions, and especially if the chlorinating process is conducted at atmospheric pressure or too high a temperature, some di-

glycerin is usually formed. In case the monochlorhydrin-carbohydrate-glycerin solution so obtained is nitrated, the resultant product will usually contain some tetranitrodiglycerin, and nitrated hydrochloric acid esters of diglycerin in addition to the nitrated components above mentioned.

In the preparation of any of the above explosives, instead of nitrating a solution containing all of the desired components, the various components may be nitrated separately or in various combinations, and the resulting nitrated products may then be combined. This particular method of effecting the nitration is claimed in my co-pending divisional application Serial No. 526,252, filed December 31, 1922.

To the explosives described herein, there may be added other ingredients which may prove desirable in the manufacture of smokeless powders and commercial explosives, such, for example, as nitrocellulose, nitro compounds, organic and inorganic nitrates (such as nitrated vegetable ivory and nitrate of soda) perchlorates and chlorates, absorbents (such as wood flour, saw-dust, etc.).

This invention is not limited to the particular materials, components, products, processes or methods described above, since obviously many changes may be made therein without departing from the spirit or scope of my invention as set forth in the appended claims.

What I claim is:

1. An explosive containing dinitrochlorhydrin and more than one nitrated carbohydrate.
2. An explosive containing dinitrochlorhydrin, a nitrated carbohydrate, nitroglycerin, and tetranitrodiglycerin.
3. An explosive containing dinitrochlorhydrin, a nitrated carbohydrate, nitroglycerin, tetranitrodiglycerin and nitrated hydrochloric acid esters of diglycerin.
4. An explosive containing dinitrochlorhydrin, nitrated sugar and nitroglycerin.
5. An explosive containing dinitrochlorhydrin, nitrated sugar, nitroglycerin and tetranitrodiglycerin.
6. An explosive containing dinitrochlorhydrin, nitrated sugar, nitroglycerin, tetranitrodiglycerin and nitrated hydrochloric acid esters of diglycerin.

7. The method of producing explosives, which consists in nitrating a solution containing monochlorhydrin, a carbohydrate and glycerin.
8. The method of producing explosives, which consists in nitrating a solution containing monochlorhydrin, sugar and glycerin.
9. An explosive containing dinitrochlorhydrin and more than one nitrated sugar.
10. An explosive containing dinitrochlorhydrin, nitroglycerin and any nitrated carbohydrate which before nitration is soluble in water at a temperature below 150° C.
11. The method of producing explosives, which consists in nitrating a solution containing monochlorhydrin and more than one carbohydrate.
12. An explosive containing dinitrochlorhydrin, more than one nitrated carbohydrate and nitroglycerin.
13. An explosive containing dinitrochlorhydrin, more than one nitrated carbohydrate, nitroglycerin, and tetrinitrodiglycerin.
14. An explosive containing dinitrochlorhydrin, more than one nitrated carbohydrate, nitroglycerin, tetrinitrodiglycerin, and nitrated hydrochloric acid esters of diglycerin.
15. The method of producing explosives, which consists in nitrating a solution containing monochlorhydrin, more than one nitrated sugar, and glycerin.
16. An explosive containing dinitrochlorhydrin, more than one nitrated sugar, and nitroglycerin.
17. The method of producing explosives which consists in nitrating a solution containing monochlorhydrin and more than one variety of sugar.
18. An explosive containing dinitrochlorhydrin, nitroglycerin and any nitrated carbohydrate which does not solidify nitroglycerin.
19. The method of producing explosives, which consists in nitrating a solution containing monochlorhydrin, a carbohydrate, glycerin, and diglycerin.
20. The method of producing explosives, which consists in nitrating a solution containing monochlorhydrin, more than one carbohydrate, glycerin and diglycerin.
21. The method of producing explosives, which consists in nitrating a solution containing monochlorhydrin, a carbohydrate, glycerin, diglycerin, and hydrochloric acid esters of diglycerin.
22. The method of producing explosives, which consists in nitrating a solution containing monochlorhydrin, more than one carbohydrate, glycerin, diglycerin, and hydrochloric acid esters of diglycerin.

WILLIAM B. STURGIS.
